BARBECUE GRILL

Alan H. Mayer, 86 Indian Tree, Highland Park, Ill.

Filed Oct. 1, 1962, Ser. No. 71,931

Term of patent 14 years

(Cl. D81—10)

FIG. 1

FIG. 2

FIG. 5

FIG. 4

I claim:

The ornamental design for a barbecue grill, substantially as shown.
